CUTTING AND FLANGING ATTACHMENT

Harry A. Lang and Roy M. Graves,
Evansville, Ind.

Application June 28, 1949, Serial No. 101,696

11 Claims. (Cl. 153—29)

1 The present invention relates to an attachment for rotary shears and flangers, the attachment being of such character as to provide for the cutting or flanging or joggling of metal sheets to produce contours of desired characteristics. The invention disclosed and claimed herein comprises certain improvements upon the invention disclosed and claimed in our co-pending application Serial Number 788,764, filed November 28, 1947 for "Cutting and Flanging Attachment." While the machine disclosed in the said co-pending application is highly effective to perform the stated functions thereof, we have found that, by the adoption of certain improvements, simplifications and amplifications of the basic concept exemplified in the disclosure of the said co-pending application, additional functions and capacities can be conferred upon a machine of the general character of that disclosed in the said co-pending application.

The primary object of the invention is to produce an attachment, readily associable with, or removable from, known types of rotary machines, for shearing, flanging, or joggling, which will operate automatically, in conjunction with such a machine, to produce a predetermined contour upon the work piece processed by that machine, and which is capable, by the substitution or shifting of its various parts, of producing a wide variety of such contours. Further objects of the invention will appear as the description proceeds.

To the accomplishment of the above and related objects, our invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a fragmentary side elevation of a rotary machine of the character above referred to, provided with cutting rolls, and showing our attachment associated therewith;

Fig. 2 is an enlarged plan view of our attachment, showing one form of work carrier and co-operating guide devices;

Fig. 3 is a further enlarged section taken substantially on the line 3—3 of Fig. 2;

Fig. 4 is a perspective view of the carrier illustrated in Figs. 2 and 3;

Fig. 5 is a perspective view of a modified form of such carrier;

Fig. 6 is a plan view similar to Fig. 2, but showing another form of carrier and modified guide means associated therewith;

2 Fig. 7 is a plan view of a further form of carrier;

Fig. 8 is a side elevation thereof;

Fig. 9 is a plan view of rectangular form of carrier with associated guide elements;

Fig. 10 is a plan view of a rhomboidal form of carrier with associated guide elements; and

Fig. 11 is a plan view of an obround carrier with associated guide elements.

10 Referring more particularly to the drawings, it will be seen that we have illustrated a part of a rotary machine of the character above discussed, indicated by the reference numeral 10. Such a machine provides a work-receiving throat 11 behind a pair of spindles upon which may be mounted rolls such as the rolls 12 and 13. In the illustrated embodiment, we have shown joggling rolls, but it will be understood that cutting rolls, flanging rolls, or rolls to perform other similar operations may be substituted for the joggling rolls 12 and 13, in a manner well known to the art.

15 A guide bed 14, having legs 15, may be associated with the machine 10 in a manner well known to the art, such guide bed providing a slideway upon which is mounted the foot 16 of a work support 20. In the illustrated embodiment, the guide bed 14 is provided with a rack 17 with which cooperates a pinion suitably journaled on the foot 16 and provided with a crank 18 for adjusting the unit 20 toward and away from the rolls 12 and 13. All of this is standard construction.

20 The unit 20 ordinarily provides a table 21 upon which is suitably mounted a base 39 having a threaded socket 22 for the reception of a centering pin or guide element 23, having a threaded portion 24, a cylindrical shank, and a hold-down head 25. A work carrier 26 is formed to provide a continuous perimetral surface 27 and a second continuous surface 28 uniformly spaced from the surface 27 in the direction of the center of the carrier 26. The inner upper surface of the carrier is rabbeted, as at 29, for the accommodation of the head 25 of the pin 23, the cylindrical section 30 of the pin shank engaging the continuous surface 28.

25 Straps or platform pieces 30 and 32, supporting work-engaging devices, herein illustrated as pins or posts 31 and 33, are suitably secured to the upper surface of the work carrier 26 in such positions as not to interfere with the guide element 23 or with the pins and/or rollers hereinafter to be described.

30 Suitably fixed to the base 39 is a rectilinear guide abutment 34 whose surface facing the guide

element 23 is preferably defined by a series of rollers 35. The perpendicular distance between the cylindrical surface of the guide element 23 and the abutment surface defined by the rollers 35 is substantially equal to the spacing between the guide surfaces 27 and 28 so that, when the carrier 26 is in place, it is confined between the abutment unit 34 and the guide means 23.

At a point spaced from the guide element 23, and upon an axis parallel to the axis of said guide element, a pin 36 projects upwardly from the top surface of the base 39. In the embodiment of the invention illustrated in Figs. 1 to 3, said pin is located upon an arc tangent to the cylindrical surface of the guide element 23 at its radius perpendicular to the surface defined by the rollers 35, and concentric with the major arc of the elliptical carrier 26, the axis of the pin being spaced from the axis of the guide element a distance somewhat less than one-half the length of such major arc. Thus, when the parts are in their illustrated positions, not only the guide element 23, but also the pin 36, will engage the carrier surface 28 to establish a movement path for the carrier.

In the illustrated form of the invention, the pin 36 is guided in a dependent strap 37, and is urged upwardly by a coiled spring 38 confined between the base of said strap and a collar 40 fixed to the pin 36, so that said pin is resiliently compressible.

At a point spaced in the opposite direction from the position of the guide element 23, a pin 41 projects upwardly from the base 39 and carries a roller 42 so positioned as to engage the surface 27 of the carrier 26 in the manner illustrated.

A piece of work 47 being supported upon the carrier 26 and engaged between the rollers 12 and 13, it will be clear that, as said rollers are driven, the work piece will be caused to move past the rollers, and the carrier will be caused to move correspondingly, being guided by the elements 23, 34, 36, and 42. As the short-radius arc at the left-hand end of the surface 28 of the carrier 26 approaches the guide element 23, the mouth of a slot 43, opening through the lower surface of the carrier 26 and extending between the surfaces 27 and 28, will approach the position of the pin 36. It will be seen that the surface 27 will now leave the roller 42. As the mouth of the slot 43 comes into registry with the pin 36, the guide element 23 will enter the short-radius curve above mentioned; and the carrier will begin to rotate, about the axis of the guide element 23, the pin 36 passing through the slot 43 and leaving the interior of the carrier. The roof of the slot 43 is inclined in the manner indicated at 45 in Fig. 3 so that, as the pin passes through the slot, the pin will be depressed against the tendency of the spring 38. This arrangement, of course, minimizes the weakening of the carrier resulting from the provision of slots like the slot 43; but, as will appear hereinafter, such slanting of the roofs of said slots is not essential.

It will be seen that the slot 43 is formed on an arc which, when said slot is in registry with the pin 36, is concentric with the guide element 23.

As the carrier completes its turn about the short-radius curve at its left-hand end, the mouth of a second slot 44, whose roof is oppositely inclined, comes into registry with the pin 36, and the pin passes again into the interior of the carrier 26. It will be seen that the slot 44 is curved as a continuation of that portion of the surface 28 immediately adjacent said slot; so

that, as the pin 36 enters the slot 44, it again begins to cooperate with the element 23 to guide the carrier on its established movement path; and, as the carrier continues to move, the pin 36 again cooperates with the surface 28.

Now, as the short-radius curve at the opposite end of the carrier approaches the element 23, a slot 45, in all respects similar to the slot 43, comes into registry with the pin 36, and the carrier makes another turn about the element 25, the pin 36 again passing outside the carrier. As the carrier completes its turn, the pin re-enters the carrier through a slot 46 similar in all respects to the slot 44.

While the structure above described performs satisfactorily on relatively light material, its performance, particularly upon heavy material, can be improved through the use of a carrier of the character generally indicated by the reference numeral 26', and illustrated in Fig. 5. The carrier 26' is formed to provide surfaces 27' and 28', entirely similar to the surfaces 27 and 28, and is rabbeted at 29'. Work-support pieces 30' and 32' carry work-engaging elements 31' and 33'; and

26 said pieces are welded to the upper surfaces of the carrier 26' and to a center piece 48 which is formed to provide a continuous surface 49 uniformly spaced from the surface 28', in the direction of the center of the carrier, and by an amount substantially equal to the diameter of the cylindrical section of the guide element 23. The head 25 of said guide element engages not only in the rabbet 29 but also in a corresponding rabbet 50 in the element 48. Additional securing straps 51 are preferably welded to the carrier 26' and to the piece 48. The embodiment of the invention illustrated in Fig. 5 operates precisely in the manner above described in connection with Figs. 1 to 4; but its operation is somewhat steadied by the presence of the center piece 48 providing its continuous surface 49 for cooperation with the element 23.

It will be apparent, of course, that the maximum projection of the pin 36 above the base 39 is substantially less than the height of projection of the guide element 23.

In Fig. 6, we have shown a triangular carrier 60 providing a continuous perimetral surface 61 and a continuous perimetral surface 62 uniformly spaced from the surface 61 in the direction of the center of the carrier. The carrier is continuously rabbeted as at 63 for cooperation with the head 25 of the guide element 23.

Straps 64, 66 and 68 carry work-engaging elements 65, 67 and 69, such straps spanning the corners of the carrier in the illustrated embodiment of the invention. A pin 70, spaced from the element 23 in the direction of rectilinear travel of the carrier, likewise engages the surface 62. As the carrier moves in the direction indicated by the arrow, a slot 71 in the under surface of the carrier approaches registry with the pin 70 as the short-radius curve 72 in the surface 62 approaches the guide element 23. When said curve engages the element 23, the carrier will be rotated in a counter-clockwise direction, the pin 70 passing through the slot 71 to the exterior of the carrier; and the carrier will continue to rotate about the axis of the element 25 until that portion of the surface 61 between the curve 72 and the curve 74, comes into engagement with the guide abutment 34. A slot 73, located as a continuation of that portion of the surface 62 between the curves 72 and 74, passes the pin 70 into the interior of the

carrier and into engagement with the surface 62, as the carrier continues to move past the guide element 23.

Similarly, when the curve 74 engages the element 23, a slot 75 will pass the pin 70 to the exterior of the carrier, as the carrier rotates about the axis of the guide element 23 with its curve 74 in engagement with said element. The pin 70 reenters the carrier through the slot 76, which is a continuation of that portion of the surface 62 between the curves 74 and 77. As the curve 77 encounters the guide element 23, a slot 79 registers with the pin 70 to permit said pin once more to emerge from the carrier as the carrier rotates, upon its curve 77, about the axis of the element 23. In its illustrated position, the pin 70 has just reentered the carrier through the slot 78, which is a continuation of that portion of the surface 62 between the curve 77 and the curve 72. The slots 71, 75 and 79 are, of course, concentric with the curves 72, 74 and 77, respectively; and they and the slots 73, 76 and 78 may have inclined roofs or not, depending upon whether the pin 70 is mounted resiliently or fixedly.

In the embodiment of the invention illustrated in Figs. 7 and 8, the carrier 80 is provided with a continuous surface 81 and a continuous surface 82 uniformly spaced therefrom in the direction of the center of the carrier, each of said surfaces having the outline of a semicircular disc. The carrier is rabbeted as at 83 to accommodate the head 25 of the guide element 23; and will preferably be provided with a center piece 84 secured in place by a strap 85 welded to the upper surfaces of the carrier 80 and to the center piece 84; and supporting work-engaging elements 86 and 87. The center piece 84 provides a continuous surface 88, uniformly spaced from the surface 82 in the direction of the center of the carrier, by an amount substantially equal to the diameter of the cylindrical shank of the guide element 23; and said piece is perimetraly rabbeted as at 89 to accommodate the head 25.

A pin 90 is spaced from the guide element 23 in the direction of carrier travel to engage the rectilinear portion 82a of the surface 82 throughout the major portion of the travel of the carrier, while the rectilinear portion of its surface 81 is engaged with the guide abutment 34. A second pin 91, substantially closer to the element 23, is positioned to engage the rectilinear portion of the surface 88 during the major portion of such travel. Spaced in the opposite direction from the element 23 is a pin 92 upon which is mounted a roller 93. The diameters of the pins 90 and 91 are substantially less than the diameter of the cylindrical section of the element 23; but the diameter of the roller 93 is substantially the same as that of said cylindrical section. The roller 93 is also somewhat vertically taller than the pins 90 and 91. During the major portion of the travel of the carrier while the rectilinear portion of its surface 81 engages the abutment 34, the roller 93 engages the rectilinear portions of the surfaces 82 and 88.

As the carrier moves from its illustrated position in the direction of the arrow, the roller 93 will pass from the interior of the carrier through the slot 94. As the short-radius curve 95 approaches the guide element 23, a slot 96 approaches registry with the pin 90 and a slot 97 approaches registry with the pin 91. When 75

the guide element 23 engages the curve 95, the carrier will swing, in a counter-clockwise direction, the pins 90 and 91 emerging from the carrier through the slots 96 and 97, respectively.

5 Continued rotation of the carrier causes the pin 91 almost immediately to reenter the carrier through the slot 98, whereafter the pin 91 engages the long-radius curved portion 82b of the surface 82 to assist the element 23, in the manner indicated in dotted lines, in establishing the movement path for the carrier. Very promptly thereafter, the long-radius curved portion of the surface 81 comes into engagement with the roller 93, further to control the movement path of the carrier.

As the short-radius curve 101 approaches the guide element 23, the surface 81 leaves the roller 93, but the pin 91 maintains its contact with the surface 82b until the curve 101 actually 20 engages the element 23. At that point, a slot 99 registers with the pin 91 and, as the carrier rotates about its curve 101, the pin 91 emerges therefrom through the slot 99.

As the carrier completes its turn, the pin 91 25 reenters the carrier through the slot 102, while the roller 93 reenters the carrier through the slot 100. Now, as the carrier moves rectilinearly, the pin 90 will reenter the carrier through the slot 102.

30 In Fig. 9, we have shown a quadrangular carrier 110 having a continuous perimetral surface 111 and a second continuous surface 112 uniformly spaced from the surface 111 in the direction of the center of the carrier, the upper 35 surface of the carrier being rabbeted as at 113 for cooperation with the head 25. A strap 114 carrying a work-engaging element 115 spans one corner of the carrier, while a strap 116 carrying a work-engaging element 117 spans an 40 opposite corner thereof.

A pin 118 is spaced from the guide element 25 in the direction of travel of the carrier, for engagement with the surface 112. As the short-radius curve 120 approaches the element 23, a curved slot 119 approaches registry with the pin 118; and as said curve 120 engages the element 23, the carrier will rotate in a counter-clockwise direction thereabout, the pin 118 emerging from the carrier through the slot 119.

50 As that portion of the surface 111 between the curves 120 and 123 engages the guide 34, the carrier will once again move rectilinearly, and the pin 118 will reenter the carrier through the slot 121. Said pin emerges again through the slot 122, as the carrier turns about its curve 123, and reenters the carrier through the slot 124 as the carrier once more moves rectilinearly. Similarly, the pin 118 will emerge through the slot 125 as the carrier rotates about its curve 126, will re-enter through the slot 127 as the carrier again moves rectilinearly; will emerge once more through the slot 128 as the carrier rotates about its curve 129, and will again enter the carrier through the slot 130 as the carrier re-approaches 65 its illustrated position.

The structure of Fig. 10 is quite similar to that of Fig. 9. The carrier 140 provides parallel, continuous, perimetral surfaces 141 and 142 and is interiorly rabbeted as at 143. The pin 144 is related to the element 23 much as is the pin 118. As the carrier continues its counter-clockwise rotation about the element 25, which is shown in engagement with the curve 146 in the surface 142, the rectilinear portion of the surface 141 approaches registry with the left of said guide element will en-

gage the abutment 34, whereafter the carrier will move rectilinearly and the pin 144 will enter the carrier through the slot 147, which is a continuation of the adjacent portion of the surface 142. The slot 148 will register with the pin 144 as the curve 149 engages the guide element 23, and the pin 144 will emerge through said slot 148 as the carrier rotates, reentering through the slot 150 as the carrier again begins to move rectilinearly. Similar slots 151, 154 and 145 provide for emergence of the pin 144 as the carrier rotates about its curves 152, 155 and 146, respectively; and the pin reenters the carrier through slots 153, 156 or 147 as said curved portions leave the guide element 23.

The obround carrier 170 of Fig. 11 provides continuous surfaces 171 and 172, and is rabbeted at 173 for cooperation with the head 25. Straps 174 and 176 carry work-engaging means 175 and 177.

A pin 178 is positioned in a manner similar to the positioning of the pins 118 and 144, and, during the major portions of the rectilinear movement of the carrier, will engage the surface 172 to assist in the establishment of the carrier movement path. A slot 179, however, registers with the pin 178 as the curve 180 engages the element 23, the pin 178 emerging from the carrier as the carrier swings in a counter-clockwise direction about the axis of the element 23. Shortly after completion of that turn, rectilinear movement of the carrier will cause the pin 178 to reenter the carrier through the slot 181 to engage the opposite portion of the surface 172, of which the slot 181 is a continuation. Similarly, as the curve 182 engages the element 23, the slot 183 will register with the pin 178 to permit said pin to emerge from the interior of the carrier, such pin reentering the carrier through the slot 184 as the carrier moves rectilinearly toward the right.

We claim as our invention:

1. In a device of the class described, a fixed base, a work carrier movably supported on said base and slide and guide means provided by said carrier and base, respectively, and cooperating to establish a movement path for said carrier relative to said base, said guide means comprising a substantially rectilinear guide abutment means fixed relative to said base, a guide element of circular cross section upstanding from said base upon an axis spaced from said guide abutment means and transverse relative to the length of said abutment means, and at least one pin upstanding from said base upon an axis spaced from said abutment means and from said guide element and parallel with said guide element axis, and said slide means including a continuous perimetral surface on said carrier slidably engageable with said abutment means, a continuous surface paralleling said first-named surface and uniformly spaced therefrom in the direction of the center of said carrier, and engaging said guide element when said perimetral surface engages said abutment means, and a plurality of

slots, each opening through the lower surface of said carrier and extending between said perimetral surface and said second-named continuous surface to pass said pin as said carrier rotates about the axis of said roller, said pin engaging said second-named continuous surface at times to assist in establishing said carrier movement path.

2. The device of claim 1 in which certain of said slots constitute extensions of adjacent portions of said second-named continuous surface.

3. The device of claim 2 in which another of said slots is spaced from a short-radius curved section of said second-named continuous surface and lies in an arc of a circle concentric with such curved section and having a radius equal to the distance between the axes of said guide element and said pin.

4. The device of claim 1 in which at least one of said slots is spaced from a short-radius curved section of said second-named continuous surface and lies in an arc of a circle concentric with such curved section and having a radius equal to the distance between the axes of said guide element and said pin.

5. The device of claim 1 in which each of said continuous surfaces takes the form of the outline of a semi-circular disc.

6. The device of claim 1 in which each of said continuous surfaces takes the form of the outline of a quadrangle.

7. The device of claim 1 in which each of said continuous surfaces takes the form of the outline of a triangle.

8. The device of claim 1 in which said carrier is provided with a third continuous surface paralleling said second-named continuous surface and uniformly spaced therefrom in the direction of the center of said carrier by a distance substantially equal to the diameter of that portion of said guide element engaging said second-named continuous surface.

9. The device of claim 8 in which each of said continuous surfaces takes the form of the outline of a semi-circular disc.

10. The device of claim 8 in which each of said continuous surfaces takes the form of the outline of a quadrangle.

11. The device of claim 8 in which each of said continuous surfaces takes the form of the outline of a triangle.
